UNITED STATES PATENT OFFICE.

THOMAS E. CARRIGAN, OF MILWAUKEE, WISCONSIN.

KNOCKDOWN BED FRAME FOR AUTOMOBILES.

Application filed April 3, 1922. Serial No. 548,176.

To all whom it may concern:

Be it known that I, THOMAS E. CARRIGAN, a citizen of the United States, and resident of Milwaukee, in the county of Milwaukee and State of Wisconsin, have invented new and useful Improvements in Knockdown Bed Frames for Automobiles, of which the following is a description, reference being had to the accompanying drawings, which are a part of this specification.

This invention relates to knock-down bed frames, and more particularly to a device of this character which is adapted for use in automobiles, and has for its object to provide an apparatus of this character which will be simple in construction, comparatively inexpensive to manufacture, and more efficient in use than those which have been heretofore proposed.

A further object of the invention is to provide a knockdown bed frame which may be readily adjusted to accommodate itself to automobiles of various sizes and types.

A still further object of the invention is to provide a device of this character which will be light and strong in construction and which may be readily folded up to occupy a comparatively small space when not in use.

A still further object of the invention is to provide an adjustable frame in which the parts may be quickly and securely locked in their open positions in order that they will not collapse when subjected to the weight of a person using the bed.

With these and other objects in view which appear as the description proceeds, the invention consists in the novel details of construction and combinations of parts more fully hereinafter disclosed, and particularly pointed out in the appended claims.

In the accompanying drawings in which like numerals designate like parts in all the views;

Figure 1 is a diagrammatic side elevational view of a motor vehicle, partly broken away, showing the present invention in place therein.

Fig. 2 is a side elevational view on an enlarged scale of a device constructed in accordance with the present invention as seen from the side opposite to that shown in Fig. 1.

Fig. 3 is a top plan view of the parts shown in Fig. 2.

Fig. 4 is an end elevational view of the parts shown in Fig. 2, as seen from the left of the said figure.

Fig. 5 is a fragmentary detail sectional view, taken approximately on the line 5—5 of Fig. 4, looking down.

Fig. 6 is a vertical sectional view taken approximately on the line 6—6 of Fig. 5, looking in the direction of the arrows.

Fig. 7 is a fragmentary plan view, partly broken away, of the canvas cover which is employed with the present frame;

Fig. 8 is a fragmentary vertical sectional view through one of the end members of the frame, showing how the canvas cover, illustrated in Fig. 7, is adjustably secured thereto; and

Fig. 9 is an elevational view of the bed frame in its folded position.

Referring more especially to Figs. 1 to 6 inclusive, the numeral 10 indicates a motor vehicle provided with the body portion 11, in which are located the usual front and rear seats 12 and 13, and upon which is supported the usual top 14.

In recent years the development of the motor vehicle has led to the practice of taking extended trips therein, which frequently extend over several days, and it is frequently desirable or necessary to spend the night where suitable accommodations are not available.

Under these circumstances it is desirable to occupy the vehicle, and it is the object of the present invention to provide a couch or bed which may be placed within the body of the vehicle to the end that the said vehicle may be used for sleeping purposes.

In order to accomplish this result, this invention provides a knock-down frame 15, composed of the pairs of side members, 16, 17, 18, and 19, which pairs of members are adjustably connected together by means of 100 collars 20, and 21, in which the said members are adapted to slide.

The members 16 and 18 are provided with the pivoted dogs or catches 22, provided with pins 23, adapted to engage the suitably spaced holes or recesses 24, with which the members 17 and 19 are provided, whereby the parts may be securely locked in any desired position. It thus results that the slide members may be adjusted to motor 110

vehicles wherein the distance between the front and rear seats 12 and 13 varies.

Pivotly secured to the member 16, as at 25, is an end member 26, while pivotly secured to the member 18, as at 27, is an end member 28, which is adapted to engage and co-act with the member 26 to constitute an adjustable end member for the frame 15. The various members may be made of tubular or angle iron construction, in order to provide combined strength and lightness and the member 28, has secured to its end one part of a hinge 29, the other part of which is secured to a collar 30, in which the member 26 is adapted to slide. A second collar 31, is slidably mounted upon the member 28, and is adapted to fit upon the end of the member 26 and to frictionally engage the same, whereby the two members 26 and 28 may be rigidly secured together in any desired positions.

In like manner the member 17 has pivotly secured to it, as at 32, a member 33, which is adapted to slidably engage a collar 34, which is pivotly connected as by the hinge 35, to a member 36, pivotly secured to the side member 19. A suitable collar 37, corresponding to the collar 31, is slidably mounted upon the end member 36, and is adapted to frictionally engage the end of the member 33 in order to lock these two members together.

The parts so far described constitute a horizontal frame which is adapted to receive the supporting canvas, as will presently appear, and in order to support the said frame within the motor vehicle body, there is provided the substantially vertical angle iron supporting legs 40, 41, 42, and 43. The leg 40 is pivotly secured to the horizontal side member 16 by means of a collar 44 slidably secured to the said side member, while the leg 41 is secured to the member 17 by a collar 45, the leg 42 is secured to the member 18 by a collar 46, and the leg 43 is secured to the member 19 by means of a collar 47. The said legs are pivoted to the respective collars transversely of the frame so that when the frame is not in use they may be swung upwardly about their pivots to occupy positions in close proximity to the slide members 16, 17, 18 and 19, respectively, and thus occupy very little space.

In order to brace the said legs transversely there is provided the horizontal bracing members 48 and 49, which members are composed of the pairs of adjustable angle members 50 and 51, 52 and 53 respectively. The said members 50 and 51 are adjustably connected together by means of the collars 54 and 55, while the members 52 and 53 are connected together in like manner by the collars 56 and 57.

The said bracing members 48 and 49 are adapted to be removably received in the enlarged sockets 60, provided within the col-

lar members 61, with which the legs 40, 41, 42 and 43 are provided and the said members 48 and 49 may be held within the said sockets by means of suitable springs 62, which force the said members 48 and 49 to one side of the said sockets 60, thereby causing the said members to engage the shoulders 63 with which the said socket members 61 are provided, as is clearly shown in Figs. 4, 5, and 6.

In order to provide for vehicles having seats such as 12 and 13, of different heights, the legs 40, 41, 42, and 43 are each provided with slidable extension members 65, having the holes or recesses 66 which are adapted to be engaged by the pins 67 carried by the collar members 68 with which the said legs 40, 41, 42 and 43 are provided, as will be clear from Figs. 2 and 4 of the drawings.

After the frame has been set up within the machine a canvas supporting member 70 may be stretched thereon, in order to support the mattress, cushions, or other bedding which is to be used. The ends of this said canvas member 70 are provided with suitable reinforced chain-like members 71 having hooks or other suitable securing members 72, which are adapted to engage the edges of the end angle iron members 26, 28, 33, and 36, as shown in Fig. 8. In order to stretch the said canvas taut, the end members 33 and 36 may be revolvably mounted upon trunnions 74 and 75 and provided with a pivoted handle 76 whereby the said members 33 and 36 may be rotated in order to stretch the canvas. Suitable ratchet wheels 77, having associated with them the dogs or pawls 78, may be provided in order to hold the parts with the canvas in its stretched position.

When it is desired to employ the present invention, it is only necessary to set up the frame with the parts in the positions illustrated in the drawings and place the same within the body of the machine, with the legs 42 and 43 occupying the space in front of the front seat and the legs 40 and 41 occupying the space in front of the rear seat. The canvas cover 70 may then be secured to the end members 26, 28, 33, and 36 by means of the hooks 72 and it may be stretched taut by operating the handle 76 in the manner above disclosed.

When it is desired to fold up the bed in the morning, the canvas may be loosened and removed and the horizontal bracing members 48 and 49 moved out of the receiving sockets 60 and folded with the legs. The legs 40, 41, 42, and 43 will then be swung upwardly into close proximity with the side members 16, 17, 18 and 19, and the hinges 29 and 35 broken, thereby permitting the end members 26, 28, 33, and 36 to swing inwardly, to occupy offset positions adjacent the said side members 10, 17, 18, and 19.

During this operation the members 26 and 33 will slide within the collars 30 and 34 as will be readily apparent. The parts may be furthermore contracted by disengaging the 5 pivot catches 22 from the holes 24 and collapsing the side members longitudinally as will be likewise readily apparent.

It will thus be seen that this invention provides a bed frame which is especially 10 adapted for use in connection with motor vehicles, which is relatively small and light in construction and which may be readily folded up to occupy comparatively little space when not in use. It furthermore provides a 15 frame which may be rapidly set up, and which is strong enough to support any weight which it may be called upon to carry.

It is obvious that those skilled in the art 20 may vary the details of construction, as well as the arrangement of parts, without departing from the spirit of the invention, and therefore, it is not wished to be limited to the above disclosure except as may be required by the claims.

25 What is claimed is:

1. In a device of the class described, a horizontal frame comprising side members and end members pivotally secured thereto, said members being adjustable longitudinally and transversely respectively to fit 30 within vehicle bodies of different sizes; and vertically adjustable supporting members pivotally secured to said frame in spaced relation, adapted to straddle a seat of said 35 vehicle.

2. A device of the class described comprising a horizontal frame consisting of longitudinally adjustable side members, and transversely adjustable end members, said 40 end members comprising readily engageable and disengageable pairs of sections pivotally secured to said side members; means for holding said pairs of sections in their engaged positions; and vertically adjustable 45 supporting members pivotally secured to said side members.

3. A device of the class described comprising a horizontal frame consisting of lon-

gitudinally adjustable side members, and transversely adjustable end members, said 50 end members comprising readily engageable and disengageable pairs of sections pivotally secured to said side members; means comprising a collar hinged to one section of each pair and a second collar slidable to 55 engage both sections of each pair for holding said pairs of sections in their engaged positions; and vertically adjustable supporting members pivotally secured to said side members. 60

4. A device of the class described comprising a horizontal frame having longitudinally adjustable side members and transversely adjustable foldable end members pivotally secured to said side members; vertically adjustable supporting members pivotally secured to said side members; and detachable bracing members secured to said 65 supporting members.

5. A device of the class described comprising a horizontal frame having longitudinally adjustable side members and transversely adjustable foldable end members pivotally secured to said side members; vertically adjustable supporting members pivotally secured to said side members; and readily foldable transverse bracing members secured to said supporting members. 70

6. A device of the class described comprising a horizontal frame having longitudinally adjustable side members and transversely adjustable foldable end members; means of locking said side and end members in their adjusted positions; means associated with one of said end members for tensioning a yieldable supporting sheet upon said frame; vertical supporting members pivotally secured to said side members; adjustable readily foldable transverse bracing members secured to said supporting members; and means for locking said bracing members in their adjusted positions. 80 85 90

In testimony whereof, I affix my signature.

THOMAS E. CARRIGAN.
